SPRAY DISPENSING BOTTLE

Donald F. Armour, Bloomfield, Conn., assignor to Monsanto Company, St. Louis, Mo., a corporation of Delaware

Filed Sept. 16, 1964, Ser. No. 81,753

Term of patent 14 years

(Cl. D58—8)

FIG. 1

I claim:

The ornamental design for a spray dispensing bottle, as shown.
